UNITED STATES PATENT OFFICE.

JOHN F. ROSEBERRY, OF BURLINGTON JUNCTION, MISSOURI.

MOTOR.

SPECIFICATION forming part of Letters Patent No. 392,290, dated November 6, 1888.

Application filed June 19, 1888. Serial No. 277,599. (No model.)

To all whom it may concern:

Be it known that I, JOHN F. ROSEBERRY, a citizen of the United States, residing at Burlington Junction, in the county of Nodaway 5 and State of Missouri, have invented a new and useful Improvement in Motors, of which the following is a specification.

My invention relates to an improvement in motors for operating pumps, churning, and other machinery; and it consists in the peculiar construction and combination of devices, that will be more fully set forth hereinafter, and particularly pointed out in the claims.

In the accompanying drawings, Figure 1 is 15 an elevation of a motor embodying my improvements. Fig. 2 is a similar view of the opposite side of the same. Fig. 3 is a vertical transverse sectional view taken on the line α α of Fig. 1. Fig. 4 is a top plan view of the 20 clock-work mechanism of my improved motor.

A represents a frame-work or scaffolding of suitable height, which is provided at one end with a tower, B, in the upper end of which is journaled a sheave, C.

D represents a shaft, which is journaled in 25 suitable bearings in the frame, has a large spur-wheel, E, which is rigid with the shaft, and has a drum, F, which is loose on the said shaft, and is connected to the wheel E by means 30 of a pawl-and-ratchet mechanism, G, whereby said drum is adapted to rotate in one direction independently of the shaft. One end of the said shaft projects beyond its bearing and is squared, and thereby adapted to be rotated 35 by the mechanism to be hereinafter described. A cord or rope, H, is secured to the drum, passes over the sheave C, and to the pendent end of said cord or rope is secured a weight, I, of suitable gravity.

K represents a shaft, which is provided with 40 the pinion L, that meshes with the wheel E, and has also a spur-wheel, M, which meshes with a pinion, N, on a counter-shaft, O. Secured to the projecting end of said counter-shaft is 45 an escapement-wheel, P, which is engaged by an anchor, R, that is pivoted on the spindle S and is adapted to move laterally thereon, so that it may be disengaged from the escapement-wheel. The said anchor is provided with 50 the usual vibrating rod, T.

U represents a pendulum-rod, which is engaged by the lower end of the rod T, and from the pendulum-rod is suspended a bob, V.

W represents a lever, which is pivoted on a suitable support and has its shorter end bifurcated and engaging opposite sides of the anchor, the function of the said lever being to move the anchor laterally into or out of engagement with the escapement-wheel. A spring, X, bears against the inner side of the 55 said lever, near the longer end thereof, the function of the said spring being to normally retain the lever in position with the anchor engaging the escapement-wheel. A cord, Y, is attached to the free end of the said lever, 60 passes through a suitable guide and depends to within easy reach of the operator, the function of this cord being to trip the lever W, so as to cause the latter to move the anchor 65 out of engagement with the escapement-wheel. 70

Z represents a shaft, which is provided with a pinion, A', that engages the wheel M, and has at its opposite end a spur-wheel, B', which engages a pinion, C', on a shaft, D'. The latter has its outer portion journaled in a lever, E', from which extends a rod, F', the outer 75 end of said rod being guided in a suitable keeper, G'.

H' represents a coiled extensible spring, which 80 is arranged on the rod F' and bears against the keeper and the lever, the function of the said spring being to so move the lever as to cause it to keep the pinion C' normally in engagement with the wheel B'. Secured to the 85 outer end of the shaft D' is a crank-wheel, I'.

A guide, K', is arranged at a suitable distance below the crank-wheel, and a rod, L', is directed by the said guide and has its upper end pivotally connected to the crank-wheel, 90 whereby, when the latter is rotated by the motor, the said rod will be caused to reciprocate, as will be readily understood, and is adapted for the attachment of the plunger-rod of a churn or pump.

When the escapement is engaged by the anchor, the pendulum is caused to vibrate and serves to cause the motor to run at a slow rate of speed; but when the lever W is turned, so as to move the anchor out of engagement with 95 100

the escapement-wheel, the pendulum is no longer vibrated, and the motor is adapted to operate at a greatly-increased rate of speed, as will be readily understood.

5. Connected to the lever E' is a cord, M', which is guided on a suitable sheave or pulley, and is adapted to move the lever E' against the tension of the spring H', so as to cause the pinion C' to be disconnected from the wheel B', and consequently throw the machine, which is operated by the motor, out of gear.

I will now proceed to describe the mechanism by means of which the drum may be rotated independently of the gearing and motor, 15 so as to wind up the cord or rope H and raise the weight.

N' represents a shaft, which is journaled in suitable bearings, is movable longitudinally therein, has a drum, O', and has its inner end 20 provided with a squared socket, P', which is adapted to receive the squared end of the shaft D.

R' represents a lever which engages the shaft N', and is adapted to move the same longitudinally in its bearings, so as to throw it into or out of engagement with the shaft D, and to the said lever is connected a hand-lever, S', which is retained in any desired position by means of a rack, T'.

30. U' represents a counter-shaft, which is provided with a pinion, V', that meshes with the wheel N², and the said shaft has a crank, W', by means of which it may be rotated so as to impart rotary motion to the shaft N', and consequently operate the shaft D, with the result before stated.

Secured to the drum O' is a rope or cord, X', which passes over a guiding-sheave, Y', and to the pendent end of the said rope is 40 attached a weight, Z'. The function of this weight is to assist the operator in rotating the shaft N' when the weight I is being elevated.

Having thus described my invention, I claim—

45. 1. The combination, in a motor, of the wheel B', the lever E', the shaft D', having one of its

bearings in said lever, for the purpose set forth, the pinion C' on said shaft adapted to engage the wheel B', the crank-wheel also secured to said shaft, and the pitman attached to said 50 crank-wheel, substantially as described.

2. The combination, in a motor, of the wheel B', the lever E', the shaft D', having one of its bearings in the said lever, the wheel I', the pinion C', the spring bearing against the said 55 lever to keep the pinion normally in engagement with the wheel B', and the operating-cord attached to said lever, substantially as described.

3. The combination, in a motor, of the escapement-wheel, the pallet movable laterally on its bearing, the pendulum connected thereto, the lever to move the pallet into and out of engagement with the escapement-wheel, and the spring X, bearing on the lever and keeping the pallet normally in engagement with the escapement-wheel, substantially as described.

4. The combination, in a motor, of the winding-shaft D, the longitudinally-movable shaft 70 N', adapted to engage said winding-shaft and having the drum, the lever arm R', attached to the shaft N', the hand-lever S', connected to the lever-arm, the rack T' to engage and retain the hand-lever, the counter-shaft having 75 the crank and geared to shaft N', the cord attached to the drum, and the weight suspended from the cord, substantially as described.

5. The combination, in a motor, of the winding-shaft D, the longitudinally-movable shaft 80 N', adapted to engage said winding-shaft and having the drum, the counter-shaft having the crank and geared to the shaft N', the cord attached to the drum, and the weight suspended from the cord, substantially as described. 85

In testimony that I claim the foregoing as my own I have hereto affixed my signature in presence of two witnesses.

JOHN F. ROSEBERRY.
